2200 Wilkinsville, Ohio, is a man with many accomplishments.

He expected a positive answer from the King, but the King's answer was not to be had for some time. Finally, he received a reply from the King, which read:

Figure 4 is a photograph in view to the east and shows the site of the old fortifications.

However, it is a bit concerning that not only does the *giant* have a very large head, but it also has a very large body.

Fig. 2 shows the sections of the two types of the *Leptothrix* which are respectively 6.56 and 1.16 microns in thickness.

It is suggested that the following steps be taken to implement the recommendations of the study:

Die 26. Februar 1850. — Einzelne Bemerkungen über die Entwicklung der Pflanzen in Südwürttemberg.

station point. A diagram of the same is given in Figure 10, showing the effect of the two types of errors on the final position of the station point.

Et quod dicitur in legge, quis diligenter servare posset, servare in amorem, hinc quod potest, non servare in deo. Et quod dicitur in statuta, id est in iuris, quod potest, servare in amorem, hinc quod potest, non servare in deo. Et quod dicitur in constitutis, id est in iuris, quod potest, servare in amorem, hinc quod potest, non servare in deo.

described in connection with the annulus *i*. The metallic rim section however, extends in a continuous piece through the annulus *p*.

While various forms of covering may be applied to the metallic rim section without departing from my invention, I find it preferable to employ a vulcanized fiber, and I have devised a novel method of in-
5 casing the metallic rim section within the fiber covering. Thus the vulcanized fibrous material is formed into tube shape upon a suitable mandrel, and while the fibrous tube is still "green" it is telescoped upon the metallic ring section and then allowed to
10 dry. Preferably the fibrous tube is formed straight and then forced upon the metallic rim section after the latter has been bent into curved form. During the drying the, shrinkage will remove all creases or the like,
15 but when a particularly smooth, hard surface is desired, the fibrous covering may be ironed while in engagement with the metallic rim section.

During the setting or hardening of the vulcanized fiber there is a tendency for it to contract. I therefore find it desirable to form the covering of the rim of a plurality of segments, two being illustrated in the structure shown in the drawings. This will
25 permit the contraction of the tubular casting without cracking or rupturing the same, while the metal bands for securing the spider arms to the rim form suitable means for taking care of any inequalities at the
30 adjacent ends of the fibrous tube, due to contraction. Another desirable method of covering the metallic rim section is to spirally wrap the latter with a suitable covering material.

40 With my improved construction of spider, the spider arms are formed of sheet metal stampings having their outer ends—as hereinbefore described—attached to the rim and having their inner ends attached to the spider center *P*. The latter is formed of two superimposed metal stampings *Q* *R* having cylindrical hubs *S* suitably secured to a bearing *T* that receives the stem of the steering post. These sheet metal stampings have radially-extending arms *U* *V* between which is arranged the inner end *W* of the spider arm, the parts *U* *V* and *W* being secured together by a rivet *X*. One of the stampings as *V* has the sides
45 provided with flanges *Y* that are turned over the edges of the other stamping. As shown in Fig. 6, the sides of the member *T* are provided with a groove *Z* forming a rectangular bearing portion *A'* which is so arranged that the corners *C'* thereof will engage the V-shaped recess *D'* in the end of the spider arm, thereby anchoring the latter against lateral play.

As all the parts of the spider except the bearing for engaging the stem of the steer-

ing post, are formed of sheet metal stampings which are so constructed as to be readily assembled, the spider may be very cheaply manufactured and also is comparatively light. If desired, the parts of the spider may be suitably grooved to add stiffness and strength thereto.

What I claim as my invention is:—

1. A steering wheel rim, comprising a rim proper having a joint, a fastening member at the joint and an outer covering of heat-insulating material substantially flush with the fastening member.

2. A steering wheel rim, comprising a rim proper, composed of a plurality of segments, an outer tubular covering of heat-insulating material formed of segments telescopically engaged with the segments of the rim proper, and means for rigidly connecting together the segments of the rim

3. In a steering wheel, a hollow metal rim, a spider having arms extending within said rim, metal bands encircling the rim, and means for connecting the spider arms, rim and bands together.

4. In a steering wheel, a hollow metal rim, a covering for said rim of heat-insulating material formed in a plurality of segments, a spider, and a band encircling said rim and connected to one of the arms of the spider, said band forming a joint between adjacent ends of two of said segments.

5. In a steering wheel, a spider composed of a member for engaging the stem of the steering post, said member being grooved to form a polygonal bearing portion, spider arms having recessed inner ends engaging corners on the polygonal bearing portion, and metal plates arranged upon opposite sides of said spider arms having hubs for engaging the ends of said member and having complementary arms secured to the spider arms.

6. In a steering wheel, a rim divided cross-wise into a plurality of segments, members embracing the meeting ends of adjacent segments for securing said ends together, and a spider having arms, the outer ends of which are attached to said members.

7. In a steering wheel, a rim divided cross-wise into a plurality of segments, means for reinforcing the rim at the meeting ends of adjacent segments, a spider having a plurality of arms the outer ends of which engage the rim at the meeting ends of adjacent segments, and securing means extending through the arms, the rim and the reinforcing means.

8. A steering wheel, comprising a rim, spokes and hub, the inner ends of the spokes being inserted in sockets formed in the hub, and a pair of sheet metal plates rigidly connecting the hub and spokes, said plates re-

spectively having central apertures engaging the hub ends, and each having radially projecting clamping portions, forming pairs with the corresponding portions of the other 5 plate to engage the inner ends of the spokes, and means rigidly connecting the coacting pairs of clamping portions with the spokes.

9. A steering wheel, comprising a rim, spokes and hub, and a pair of sheet metal 10 members arranged one at each side of the hub, forming in conjunction two-part sleeves receiving the inner ends of the spokes, sockets being formed in the hub receiving the inner ends of the spokes, and means 15 rigidly connecting said plates.

10. A steering wheel comprising a rim, a spider including a hub, arms radial thereto and sockets projecting from the hub receiving the inner ends of the arms, and members 20 forming the connections between said sockets and arms passing through the latter.

11. A steering wheel, comprising a rim, spokes and hub, and a sheet metal plate connecting the hub and spokes, sockets 25 being formed in the hub receiving the inner ends of the spokes, said plate having a central aperture engaging the hub end, said end being formed with a shoulder as an abutment for the edge of said plate peripheral to the central aperture of said plate.

12. The combination with a hub piece provided with a circumferential groove having its bottom shaped to constitute a plurality of spaced abutments, a shoulder being 35 formed at one end of said hub piece, a plurality of spokes having their inner ends engaging with and of complementary contour to the abutment portions of said groove, a pair of sheet metal members keyed on said 40 hub, one at each side of the spokes and coacting to engage the inner ends of the spokes, one of said members being held in place through engagement with said shoulder, fastening members passing through the 45 registering portions of said spoke and sheet metal members and a rim to which the outer extremities of the spokes are attached.

13. In a steering wheel, a spider comprising an apertured member for engaging the 50 stem of the steering post, said member having an exterior polygonal bearing portion, spider arms having recessed inner ends engaging apices of said polygonal portion, and a pair of members mounted upon the respective end portions of said apertured member and rigidly engaging the spider arms 55 respectively at each side of said arms.

14. In a steering wheel, a spider comprising a member for engaging the stem of the 60 steering post, spider arms having their inner ends abutting against said member, said ends and the faces against which they abut being shaped to prohibit relative rotation, and a pair of sheet metal plates mounted 65 upon the respective end portions of said

member and rigidly engaging the spider arms respectively at each side of said arms.

15. In a steering wheel, a rim having meeting ends, a metal band surrounding said meeting ends, and retaining the same in a 70 fixed relation, and a spider having arms secured to the rim, the outer end of one of said arms being attached to the extremities of said band.

16. In a steering wheel, a rim having 75 meeting ends, a metal band surrounding said meeting ends, a spider having arms secured to the rim, the outer end of one of said arms being extended into the rim at the juncture of said ends, fastening members engaging 80 the metal band with said meeting ends of the rim and also engaging said arm, and means engaging the extremities of said metal band with said arm.

17. In a steering wheel, a spider comprising an apertured member for engaging the stem of the steering post, said member having an exterior polygonal bearing portion, spider arms having recessed inner ends engaging apices of said polygonal portion, 90 and a member mounted upon an end portion of said apertured member and rigidly engaging the spider arms.

18. In a steering wheel, a spider comprising a member for engaging the stem of the 95 steering post, spider arms having their inner ends abutting against said member, said ends and faces against which they abut being shaped to prohibit relative rotation, and a sheet-metal plate mounted upon an end 100 portion of said member and rigidly engaging the spider arms.

19. In a steering wheel, a spider composed of a member engaging the side of the steering post, said member being grooved to form 105 a polygonal bearing portion, spider arms having recessed inner ends engaging corners on the polygonal bearing portion, and a metal plate arranged at one side of said spider arms mounted upon an end portion 110 of said member and having complementary arms secured to the spider arms.

20. A built-up steering wheel comprising a rim portion, a spider portion, said spider portion comprising a plurality of separate 115 sheet metal spider arms extending from the rim portion to the central part of the wheel only and superimposed, sheet metal stampings arranged on opposite sides of the inner ends of said arms, one of said stampings 120 having a portion at the hub extending transversely to the main body portion of the stamping and each of said arms being directly secured to at least one of said stampings.

21. A built-up steering wheel comprising a rim portion, a unitary rigid central fitting and a spider portion, said spider portion comprising a plurality of independently 130 formed spider arms extending only from the

rim portion to the central fitting and each secured thereto in permanently fixed relation to the other arms, said central fitting having a main body portion directly secured to the inner ends of said arms and terminating in a portion at the hub extending transversely to the main body portion.

22. A built-up steering wheel comprising a rim portion and a spider portion, said spider portion comprising a plurality of independently formed spider arms, each arm being formed independent of the remaining arms, the outer end portions of said spider arms being secured in fixed relation with the rim portion, and the inner ends of said arms being secured in permanently fixed relation to the other arms.

23. A built-up steering wheel comprising a rim portion, a hub portion and a spider portion, said spider portion comprising a plurality of independently formed spider arms extending from the rim portion to the hub portion only, the outer ends of said arms being secured in fixed relation with the rim portion and the inner ends of the arms being secured in permanently fixed relation with the hub portion.

24. A built-up steering wheel comprising

a rim portion, a hub portion made up of parts rigidly secured together in permanently fixed relationship, and a spider portion, said spider portion comprising a plurality of independently formed spider arms extending from the rim portion to the hub portion only, the outer end portions of said arms being secured in fixed relation with the rim portion, and the inner end portions of the arms being secured in fixed relation with the hub portion.

25. A built-up steering wheel including a rim portion and a spider portion, said spider portion comprising a plurality of independently formed spider arms, each of said arms consisting of a sheet metal stamping independent of the remaining arms, the outer end portions of the spider arms being secured in fixed relation with the rim portions and the inner ends of said arms being secured in permanently fixed relation to the other arms.

In testimony whereof I affix my signature in presence of a witness.

CHAS. W. BECK.
